BRASSIERE

Larry L. Krieger, 1030 S. Governors Ave., Dover, Del.

Filed Jan. 13, 1960, Ser. No. 59,036

Term of patent 14 years

(Cl. D20—4)

The figure on the drawing is a plan view of a brassiere, showing my new design. The essential feature of my design resides in the portions shown in full lines on the drawing.

I claim:

The ornamental design for a brassiere, substantially as shown and described.
